STEAM CONDENSER AND WATER
PREHEATERWilson L. McLaughlin, Herrold L. McLaughlin,
and Virg Ballou, Des Moines, Iowa

Application July 16, 1932. Serial No. 622,984

4 Claims. (Cl. 257—43)

This invention relates mainly to a steam condensing device and is particularly adapted for use in such systems of distilling water as taught in our co-pending application for United States

Letters Patent on a process relating to the production of distilled water, filed June 16, 1932, and given Serial Number 617,638.

The principal object of our invention is to condense steam and pre-heat water for a steam generator by means of each other in a single operation.

More specifically the object of our invention is to provide a device that will condense steam and pre-heat undistilled water entering the device by bringing the steam in close proximity to the water whereby the steam will be condensed and the undistilled water heated.

A further object of our invention is to provide a steam condenser and water pre-heater that is under the control of the operator at all times.

A still further object of our invention is to provide a steam condenser that removes obnoxious odors and undesirable gases from the steam and condensed water therefrom.

A still further object of our invention is to provide a highly efficient steam condenser and water pre-heater that is economical in manufacture and durable in use.

These and other objects will be apparent to those skilled in the art.

Our invention consists in the construction, arrangement, and combination of the various parts of the device, whereby the objects contemplated are attained as hereinafter more fully set forth, pointed out in our claims and illustrated in the accompanying drawings, in which:

Fig. 1 is a side view of our complete device with sections cut away to more fully illustrate its interior construction.

Fig. 2 is an enlarged view of the discharge end of one of the steam tubes.

Fig. 3 is an enlarged top view of the discharge end portion of one of the steam tubes showing an extension trough mounted therein.

Fig. 4 is a top plan view of a portion of the distilled water agitating rack.

Fig. 5 is an end view in sections of the condenser housing showing the distilled water agitating means therein with prime mover for actuating the same.

Fig. 6 is a side view of the bracket for slidably holding the reciprocating shaft of the water agitating member.

Although steam condensers have been used for

many years and their wide employment is increasing as time goes on, little if any change has taken place in their general construction and method of operation. Their chief objection is their inability to save and utilize for useful purposes the valuable heat lost by the steam and distilled water during the condensing and cooling phase. We have overcome such objections, as will be appreciated by those skilled in the art.

Referring to the drawings, we have used the numeral 10 to designate the steam condenser and undistilled water pre-heater housing. The numeral 11 designates a tube plate inside the housing 10 and near its rear end. The numeral 12 designates a second tube plate in the housing 10 and positioned near the forward end of that housing. These two tube plates 11 and 12 create the compartments 13, 14, and 15 inside the housing 10. The numeral 16 designates a horizontal dividing plate inside the compartment 13 for dividing the compartment 13 into an upper and a lower chamber. The numeral 17 designates a similar horizontal dividing plate in the compartment 15 for dividing the compartment 15 into an upper and a lower chamber. These plates 16 and 17 are of suitable material and of substantial thickness for insulating purposes and the plate 17 is positioned in a plane lower than the plane of the plate 16. The numeral 18 designates a steam pipe discharging into the upper portion of the compartment 17. The numeral 19 designates a manually operated valve in the pipe 18 for closing, opening, or restricting that member. The numeral 20 designates a pressure gauge communicating with the inside of the pipe 18. The numeral 21 designates a plurality of spaced apart steam tubes extending completely through the compartment 14 and having their rear ends communicating with the inside of the upper chamber of the compartment 13 and their forward ends communicating with the inside of the upper chamber of the compartment 15, as shown in Fig. 1. The numeral 22 designates a trough member of circular form inserted into the forward or discharge end of each of the pipes 21.

These troughs 22 have both ends open and extend further into the compartment 15 as they collectively progress upwardly, as shown in Fig. 1. The numeral 23 designates the slot opening in the top of each of the trough members.

The numeral 24 designates a plurality of spaced apart horizontal tubes extending completely through the compartment 14 and having their forward ends communicating with the inside bottom portion of the upper chamber of the

compartment 15 and their rear ends communicating with the inside upper portion of the lower chamber in the compartment 13. The numeral 25 designates a plurality of spaced apart horizontal tubes extending completely through the compartment 14 and having their rear ends communicating with the inside bottom portion of the lower chamber of the compartment 13 and their forward ends communicating with the inside of the lower chamber of the compartment 15, as shown in Fig. 1. The numeral 26 designates a distilled water outlet pipe communicating with the inside of the lower chamber of the compartment 15. The numeral 27 designates a manually adjustable valve in the pipe 26 for the controlling of the passage of liquid therethrough. The numeral 28 designates a temperature gauge for registering the temperature of the liquid passing through the pipe 26. The numeral 29 designates a similar temperature gauge for registering the temperature inside the compartment 15 at a substantial height above the plate 17. The numeral 30 designates a water gauge having its lower end communicating with the inside bottom of the compartment 15 and its upper end communicating with the inside top of the compartment 15.

The numeral 31 designates a pipe having one end communicating with the inside forward bottom of the compartment 14 and its other end designed to be in communication with a source of cold undistilled water. The numeral 32 designates a manually controlled valve in the pipe 31 for controlling the flow of liquid through the pipe 31. The numeral 33 designates a temperature gauge for registering the temperature of the liquid passing through the pipe 31.

The numeral 34 designates a water pipe having one end communicating with the inside rear end top of the compartment 14 and its other end designed to lead to the point of use of the undistilled water warmed and heated in the condensing of the steam inside the housing 10. In most instances this warmed undistilled water will lead to the steam generator and due to its warm condition will not require a great deal of additional heat to reduce it to steam. Although our device is particularly designed for this method of hook-up in the distilling of water, the undistilled water so warmed may be used to equal advantages for other purposes where hot water is desired. The numeral 35 designates a temperature gauge for registering the temperature of the undistilled water passing out of the compartment 14 through the pipe 34. By this construction above described, the steam will first enter the upper chamber of the compartment 13. From this chamber the steam will pass through the pipes 21 in order to enter the upper chamber of the compartment 15. As the pipes 21 pass through the compartment 14 and are surrounded by water in the compartment 14 the steam will condense while passing through the pipes and will seek the bottom of the compartment 15 in the form of hot distilled water. By the use of the troughs 22 the drops of condensed water will fall through space in order to reach the collected water in the compartment 15 and above the plate 17. This dropping of the water through the space in the compartment 15 will naturally aid and assure the condensation of any steam that may have passed through the pipes 21 into the compartment 15. Furthermore, the dropping of this distilled water through the space in the compartment 15 and the splash-

ing of the same upon striking the collected distilled water in the lower portion of the upper chamber of the compartment 15 will aid in the liberating of any obnoxious or undesirable gases existing in the same.

Without the trough members 22 the distilled water would merely trickle down the side of the partition 12. By the troughs 22 extending further into the compartment 15 as they collectively progress upwardly the drops falling from the upper troughs will not interfere with or engage the lower disposed troughs. This hot distilled water will next pass from the upper chamber of the compartment 15 by way of the tubes 24 to the upper inside of the lower chamber in the compartment 13. As the tubes 24 pass through the compartment 14 and are surrounded by the oncoming undistilled water this distilled water upon reaching the lower chamber of the compartment 13 will be substantially cooled by giving up much of its valuable heat to the undistilled water. This distilled water next passes downwardly in the lower chamber of the compartment 13 to again pass forwardly through the pipes 25 to the inside of the lower chamber of the compartment 15. As the tubes 25 pass through the lower portion of the compartment 14 and are surrounded by the cold incoming undistilled water, the distilled water reaching the lower chamber of the compartment 15 will be relatively cold, having lost a further substantial amount of heat to the cold incoming undistilled water. From the lower chamber of the compartment 15 the cold distilled water passes through the pipe 26 to useful purposes. It will here be noted that the outlet point of the distilled water is in close proximity to the inlet point of the undistilled water and that the outlet point of the hot undistilled water is in close proximity to the inlet point of the hot steam to be condensed. By this arrangement, the undistilled water passing from the device will be at a very high temperature, while the distilled water passing from the device will be at a very low temperature approximating that of the undistilled water entering the device. This is highly desirable, as most of the valuable heat usually lost in the condensing of steam is retained by being transferred to the cold undistilled water entering the apparatus.

In fact, the undistilled water leaving the device is of such high temperature that very little additional heat is necessary to reduce it to steam. By the use of our device distilled water may be produced exceptionally economically.

In order that our device may be under the control of the operator at all times and that it may function with a maximum amount of efficiency, we have provided the necessary control valves 19, 27, and 32. The level of the hot distilled water in the upper chamber of the compartment 15 should be maintained just below the lowest pipes 21. The plates 16 and 17 not only act as guiding baffle members to the travel of the steam and distilled water, but prevent, due to their insulating properties, the re-heating of the distilled water at any point in its cooling travel through the device.

It has been found that distilled water often still contains obnoxious odors and gases as we have herebefore suggested. To further release any such undesirable gases, we provide a mechanical distilled water agitating device which we will now describe. The numeral 36 designates a slidably mounted shaft extending completely through the compartment 15 and just

above the plate 17, as shown in Fig. 1. Packing nuts 37 prevent the leakage of distilled water at points where this shaft pierces the housing 10, as shown in Fig. 5. The numeral 38 designates 5 horizontal cross bars spaced apart and secured to the shaft 36. The numeral 39 designates a plurality of vertical pins secured to each of the cross bars 38. These pins 39 should be of such height as to extend downwardly almost to the 10 surface of the plate 17 and upwardly to approximately the normal water level of the distilled water in the upper chamber of the compartment 15.

The numeral 40 designates a bracket secured 15 to the side of the housing 10 and slidably supporting the square end portion 41 of the shaft 36 outside of the housing 10, as shown in Fig. 6. The bracket 40 and square end portion 41 prevent the rotation of the shaft 36, but permits its 20 reciprocation. The numeral 42 designates a prime mover having the driving wheel 43. The numeral 44 designates a connecting arm having one end pivoted to the wheel 43 some distance from the center of the wheel 43 and its other end pivoted to the square end portion 41 of the shaft 25 36. By this construction, when the prime mover 42 is rotating the agitating rack comprising the shaft 36, cross bars 38, and pins 39, will be reciprocated through and in the hot distilled water 30 above the plate 17. Released gases from the steam and condensed water will pass to the inside top of the compartment 15. We remove such gases from the inside top of the compartment 15 by a motorized vacuum pump 45, shown in conventional form in Fig. 1. In order to encourage 35 the removal of these undesirable gases and to further purify the inside of the compartment 15, we have provided an air inlet pipe 46 communicating with the inside top of the compartment 15 and positioned some distance from the vacuum pump 45, as shown in Fig. 1. The free end of this pipe 46 has a funnel portion 47 closed by a suitable air strainer 48.

Generally speaking, the hot steam and distilled 40 water travel downwardly in an opposite direction to the travel of the cold undistilled water entering the apparatus and which travels upwardly. From the foregoing, it will be seen that we have provided a device that condenses the steam and 45 cools the distilled water and at the same time pre-heats the undistilled water by bringing the steam and distilled water in close proximity to the undistilled water in such manner that heat from the steam and distilled water are transferred to the undistilled water.

Some changes may be made in the construction and arrangement of our improved steam condenser and water pre-heater without departing from the real spirit and purpose of my invention, and it is our intention to cover by our claims 50 any modified forms of structure or use of mechanical equivalents which may be reasonably included within their scope.

We claim:

65 1. In a device of the class described, a housing, a steam compartment in one end of said housing, a distilled water compartment in the other end of said housing, a central undistilled water compartment in said housing, a plurality of tubes extending through said central compartment and communicating with said steam and said distilled water compartments, a steam pipe

discharging into said steam compartment, a distilled water outlet pipe operatively communicating with the inside of said distilled water compartment, an undistilled cold water inlet pipe communicating with the inside of said central compartment, an undistilled water outlet pipe leading from said central compartment, and trough members in each of the said tubes and extending into the said distilled water compartment.

2. In a device of the class described, a housing, a steam compartment in one end of said housing, a distilled water compartment in the other end of said housing, a central undistilled water compartment in said housing, a plurality of tubes extending through said central compartment and communicating with said steam and said distilled water compartments, a steam pipe discharging into said steam compartment, a distilled water outlet pipe operatively communicating with the inside of said distilled water compartment, an undistilled cold water inlet pipe communicating with the inside of said central compartment, an undistilled water outlet pipe leading from said central compartment, an agitating rack in the bottom portion of said distilled water compartment, and a means for actuating said rack.

3. In a device of the class described, a housing, a compartment in the rear end of said housing, a compartment in the forward end of said housing, a central compartment in said housing, a plurality of spaced apart horizontal tubes arranged in a plurality of planes and extending through said central compartment and communicating with the inside of both of said end compartments, a steam pipe discharging into the rear end compartment, a distilled water outlet pipe operatively communicating with the inside bottom of the forward end compartment, a cold fluid inlet pipe communicating with the inside of said central compartment, a fluid outlet pipe communicating with the inside of said central compartment, and a trough member open at both ends and top mounted in each of the said tubes and extending into the forward end compartment; said trough members extending further into said end compartment as they collectively progress upwardly.

4. In a device of the class described, a housing, a steam compartment in said housing, a distilled water compartment in said housing, a cold undistilled water compartment in said housing, a plurality of horizontal tubes extending through said cold undistilled water compartment and communicating with said steam and said distilled water compartments, a steam pipe discharging into said steam compartment, a distilled water outlet pipe operatively communicating with the inside of said distilled water compartment, a cold undistilled water inlet pipe communicating with the inside of said cold undistilled water compartment, a cold undistilled water outlet pipe leading from said cold undistilled water compartment, and a trough member extending from the end of each of said tubes that extend into the distilled water compartment; said trough members extending further into said distilled water compartment as they collectively progress upwardly.
